INK ROLLER VIBRATING MECHANISM

Harold W. Gegenheimer, Darien, Conn., and Samuel Davis Robins, Lawrence, N. Y., assignors to William Gegenheimer Co., Inc., Brooklyn, N. Y., a corporation of New York

Application January 4, 1955, Serial No. 479,716

8 Claims. (Cl. 101—348)

The present invention relates to inking rolls for printing presses and has specific reference to an improved vibrating inking roll of the type employed in printing presses for effecting an even distribution of ink upon the large inking cylinders.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a longitudinal sectional view of a preferred embodiment of the inking roll of the present invention showing in detail the mechanism for producing longitudinal reciprocation or vibration of the roll;

Figure 2 is a perspective view of one of the nuts or cam follower assemblies with the end of the actuating lever received in the slot formed in the bottom thereof;

Figure 3 is a perspective, exploded view of one of the helical cam members and the radial cam members associated with each end thereof; and

Figure 4 is a sectional view taken along line 4—4 of Figure 3 and showing one of the radial cams.

As is well known in the art pertaining to printing machines, in the inking operation ink is applied intermittently to a large inking cylinder by means of an oscillating roll or applicator. In order to transform this intermittent ink supply into an evenly distributed film suitable for application to the form or plate, relatively small inking rolls are positioned about and in contact with an inking cylinder causing the ink to be uniformly distributed on the periphery of the cylinder before the ink is applied to the form or plate. These inking rolls are in contact with the cylinder or with form inking rolls, and are vibrated or reciprocated in an axial direction which, together with the close proximity of adjacent rolls, makes it desirable that their mass be a minimum and their diameter and overall length be as small as practicable and also that they be simply constructed.

It is the object of the present invention to provide an improved inking roll that is automatically reciprocated in response to rotation of the roll and yet is simple in construction and has a minimum overall length and a small diameter. A further object is to provide an improved inking roll that is automatically reciprocated in response to rotation of the roll and wherein the actuating mechanism for producing reciprocation of the roll is positioned entirely within the roll in a manner so that it can be packed in grease and where it is free from possible damage as well as from being fouled by foreign mat-

2

ter. A still further object is to provide an improved vibrating inking roll that is compact yet highly reliable in operation and in which the rotating and reciprocating portion is of minimum weight.

5 In the present invention the roll includes a cylindrical sleeve that is journaled upon a pair of axially aligned, spaced spindles which are held in a suitable frame or support. The sleeve is journaled to the spaced spindles in a manner which provides not only for rotation of the sleeve about its axis, but also axial reciprocation of the sleeve upon the spindles through a given or predetermined amplitude. In operation of the device the outer surface of the sleeve contacts an inking cylinder of a printing press or another inking roll which is rotating thereby causing the inking roll to rotate about its axis. In response to this rotation of the roll, mechanism within the sleeve is effective to axially reciprocate the sleeve through a predetermined amplitude. As embodied this mechanism comprises a pair of internal helical cams of opposite pitch positioned within the sleeve in a manner so they are moved with the sleeve, with the cams being coaxial with the sleeve and spaced longitudinally from one another. Also positioned within the sleeve and radially inward of the cams are a pair of cam followers each of 10 which is mounted in a suitable bore provided in a stationary frame secured to and positioned intermediate the spindles so that the followers are restrained against movement with the sleeve but are permitted to move a limited distance laterally of the sleeve, and have slight angular 15 motion within their bores so that they may seat properly within the helical cams. Each of the followers cooperates with a different one of the cams and is laterally movable between a position in engagement with its associated cam and out of engagement with its associated 20 cam with longitudinal movement of the sleeve in response to rotation of the sleeve being effected in one direction when one of the followers is in its engaged position and in the opposite direction when the other follower is in its engaged position. Automatic actuation of the followers 25 is achieved by a concentric cam surface positioned at the end of each of the helical cams so as to be engaged by the follower to cam the follower from its engaged to its disengaged position. This lateral movement of one of the followers from its engaged to its disengaged position is 30 transmitted through a pivotal lever to the other follower to move it from its disengaged to its engaged position. Thus, when each of the followers reaches the outer end of its associated cam, which respectively correspond to the extremities of reciprocal movement of the sleeve, the 35 followers are automatically shifted or moved laterally to their other position thereby reversing the longitudinal movement of the sleeve resulting in vibration or continuous reciprocation of the sleeve as long as it is rotated.

It will be understood that the foregoing general description and the following detailed description as well are exemplary and explanatory of the invention but are not restrictive thereof.

Referring now to the present preferred and illustrative embodiment of the invention shown in the accompanying drawing and wherein like reference characters designate like elements, the inking roll depicted therein comprises a cylindrical sleeve 10 journaled upon the spaced and axially aligned spindles 12 and 14 by means of bearings 16 and 18, respectively. The aligned spindles are held fast in a suitable frame, not shown, and the bearings, which may be of any desired conventional variety, provide not only for rotation of the sleeve about its axis, which corresponds with the axis of the spindles, but also for axial reciprocation of the sleeve with respect to the spindles with the bearings moving axially with the sleeve and along the spindles and being constructed to retain lubricant within the sleeve.

The outer surface of sleeve 10 is adapted to contact a rotating inking cylinder of a printing press for the purpose of effecting an even distribution of the ink and upon contact with this cylinder the sleeve is rotated about its longitudinal axis.

In order to produce a more even distribution of the ink, the sleeve is reciprocated axially through a given amplitude, this being termed "vibration" in the printing art, and for this purpose the oppositely pitched internal helical cams 22 and 24 are secured within the sleeve, coaxial therewith and so that they move with the sleeve. These cams preferably take the form of an internal, square thread provided in cylindrical members 23 and 25, respectively, which are snugly fitted within the cylindrical sleeve and are secured to the sleeve in any desired manner with the cams being longitudinally spaced from each other by the spacer rings 26 and being spaced from the bearings 16 and 18 by spacer rings 28.

Cooperating with helical cams 22 and 24, respectively, in a manner to produce reciprocation of the sleeve are cam follower assemblies 30 and 32 mounted in the stationary support member 34 which is positioned within sleeve 10 and helical cams 22 and 24 and is bored to receive the inner ends of spindles 12 and 14 with set screws 36 positively securing the support member to the spindles. The cam follower assemblies 30 and 32 are slidably and rotatively mounted in cylindrical bores 38 and 40, respectively, extending laterally through the stationary support member thereby permitting angular movement of the assemblies about their axes in order to obtain proper seating of the follower within the helical cam and also permitting lateral movement of each of the follower assemblies intermediate a radially outward position where the follower engages its respective cam and a radial inward position where it is free of or out of engagement with its respective cam, with follower assembly 30 being shown in the engaged position in Figure 1.

Each of the cam follower assemblies includes a wheel or roller 42 rotatably mounted on shaft 44 by means of bearing 46 with the shaft being secured in cylindrical frame 48 which is received within the respective bore in support member to provide for angular movement thereof about its axis as well as reciprocation thereof within the bore. The follower assemblies are retained in their radial innermost and outermost positions in their respective slot by spring pressed detent 50 positioned in the bore 52 provided in stationary support member 34 and which cooperates with the laterally spaced grooves 54 in the face of frame 48. These grooves are so positioned that when the detent is in the outermost groove the follower assembly occupies its radial outer or cam engaging position while when in the innermost groove the follower assembly occupies its radial inner or cam disengaged position.

Positioned intermediate cam follower assemblies 30 and 32 and within the elongated slot 56 formed in support member 34 is lever 58 pivotally mounted about the pivotal support 60 and having its opposite ends respectively received within recesses 64 provided within the frames of the respective assemblies and bearing against the upper surface of these recesses. By mounting lever 58 in this manner, when one of the follower assemblies is moved inwardly from its cam engaging position to its cam disengaging position the other follower assembly will be simultaneously moved outwardly, through action of the lever, from its cam disengaging to its cam engaging position. Angular movement of the follower assemblies about their axis is limited by reception of the ends of lever 58 within the recesses 64 and 66 with these recesses being so related to the ends of the lever as to permit sufficient angular movement of the assemblies that the plane of wheel 42 may be askew of the axis of sleeve 10 an angle equal to the pitch of the helical cams so

that the wheel will rest flat against the wall of cam and fit properly in the groove of the cam.

When the follower assemblies are in their outermost or cam engaging position roller or wheel 42 is positioned 5 within the groove of the cam and in the embodiment shown when follower assembly 30 is in its cam engaging position in engagement with cam 22 and sleeve 10 is rotated in a clockwise direction as viewed from its left end the sleeve will be moved longitudinally to the right as viewed in the drawing while engagement of follower 10 42 with cam 24 will move the sleeve longitudinally in the opposite direction i. e., to the left as viewed in the drawing.

In order to produce a continuous reciprocation or vibration of the sleeve as long as it is rotated, movement of the cam followers to and from their engaged and disengaged position is automatically effected and for this purpose the eccentric camming surface 62 is provided at the ends of the helical cams with this camming surface 15 having a gradually decreasing depth which is effective to cam the follower assembly laterally to its innermost or disengaged position. As is evident from Figure 3 camming surface 62 is preferably formed on the extensions or projections 68 of the spacer rings 26 and 28 20 with these projections being received in milled slots 70 provided in the ends of cylindrical members 23 and 25 so the concentric cams form a smooth juncture with the root of the internal square thread in these members. The camming surfaces 62 are not helical but are circumferential so that they are not effective to cause axial movement of the sleeve when engaged by follower wheel 25 42 but merely cam the follower assembly radially from its outer engaged position to its inner disengaged position. The cams 62 are provided at each end of the 30 cylindrical members 23 and 25 in order that the roller may operate regardless of the direction of rotation of the sleeve thereby enabling the roller to be assembled in the printing press indiscriminately with respect to such rotation.

40 This lateral camming of the follower assembly to its disengaged position when the full length of the particular cam has been traversed causes the other follower assembly to simultaneously move to its engaged position through the action of pivotal lever 58 with the cams 45 and follower assemblies being so arranged and the helical cams 22 and 24 being in phase so that as one follower assembly reaches the end of its travel in its associated cam and is moved to its disengaged position the other follower assembly is positioned at the beginning of its associated cam and is simultaneously moved to its engaged position. By having helical cams 22 and 24 in the form of square threads these cams do not exert a radial thrust 50 against the respective follower assemblies which would tend to move the engaged follower assembly to its disengaged position.

55 In operation, when sleeve 10 is rotated in a clockwise direction as viewed from its left end, cam follower assembly 30 will engage helical cam 22 (this position being shown in Figure 1) and with the follower assembly 60 being held stationary in support member 34 the sleeve will be moved axially to the right. During this movement follower assembly 32 occupies its innermost or disengaged position free of its associated cam 24. As follower assembly 30 reaches the outer end of cam 22 it is cammed by camming surface 62 to its innermost or disengaged position and follower assembly 32 is simultaneously moved from its disengaged position to its engaged position with the inner end or beginning of helical cam 24 whereupon sleeve 10 is moved in the opposite direction with the cam follower assemblies being shifted and the direction of movement of the sleeve being reversed when each of the followers reaches the end of its travel in its associated cam thus continuously reciprocating the sleeve in response to rotation of the sleeve with the respective follower assemblies causing movement of 70 75

the sleeve in the opposite direction when the direction of rotation of the sleeve is reversed. During lateral movement of the sleeve the spring pressed detents 50 are positioned in the appropriate groove provided in each of the cam follower assemblies thereby preventing the follower assemblies from being accidentally displaced.

In assembling the inking roll of the present invention the internal mechanism is initially packed in grease or other suitable lubricant and since the bearings 16 and 18 closely fit the smooth spindles 12 and 14, respectively, so there is little or no leakage of the lubricant, substantially no maintenance of the device is required.

With the organization of the present invention an extremely compact automatically vibrating inking roll is provided which is inherently balanced for rotation about its axis without the use of special counter weights, which is no longer than the minimum length of roller desired and which has a small diameter. Furthermore with the novel construction of this invention the weight and consequently the inertia of the reciprocating portions of the roll are a minimum and yet relatively heavy and frictionless cam followers provided with a wheel or roller may be employed.

The invention in its broader aspects is not limited to the specific mechanisms shown and described but departures may be made therefrom within the scope of the accompanying claims without departing from the principles of the invention and without sacrificing its chief advantages.

What is claimed is:

1. An inking roll for a printing press comprising a cylindrical sleeve, a pair of spaced, fixed, axially aligned spindles upon which said sleeve is journaled both for axial rotation and axial reciprocation through a predetermined amplitude, a pair of internal helical cams of opposite pitch disposed within said sleeve for movement therewith, said cams being coaxial with said sleeve and being axially spaced from one another, a stationary support member disposed intermediate said spaced spindles and secured thereto, said support member being positioned radially within said cams, a pair of cam followers snugly but slidably mounted within lateral slots formed in said support member so as to be laterally movable to and from a cam engaging position and a cam disengaging position but restrained against movement with the sleeve and cams with each of said followers being associated with a different cam and cooperating with said cams to effect reciprocation of said sleeve, each of said cam followers including a rotatably mounted wheel that engages the cam when the follower is in its engaged position, a lever interposed between said followers and pivoted to said support member at a location generally centrally intermediate said followers with the ends of said lever being loosely engaged with the cam followers, said lever being effective to move one follower from its disengaged to its engaged position in response to the other follower moving from its engaged to its disengaged position, and a concentric cam provided at the end of each of the helical cams operative to cam the engaged follower laterally to its disengaged position.

2. An inking roll as defined in claim 1 wherein the cam followers are mounted for limited angular movement about the axis parallel with the direction of their lateral movement to provide for proper seating of the follower within the cam.

3. An inking roll as defined in claim 2 wherein the means whereby the sleeve is journaled to the spindles is constructed and arranged to inhibit the escape of grease from the interior of the spindle.

4. An inking roll as defined in claim 2 wherein the cam followers are mounted for limited angular movement about their axis parallel with the direction of their lateral movement to provide for proper seating of the follower within the cam with this angular movement being limited

by the interconnection between the respective follower and the lever.

5. An inking roll for a printing press comprising a cylindrical sleeve, a pair of spaced, fixed, axially aligned spindles upon which said sleeve is mounted for rotation about its major axis and for axial reciprocation through a predetermined amplitude, a pair of internal helical cams of opposite pitch disposed within said sleeve for movement therewith and in coaxial relation therewith with the cams being in closely spaced relation, a stationary support member disposed intermediate said spaced spindles and secured thereto, a first generally cylindrical cam follower means snugly but slideably received within a lateral bore provided in the support member so that it may move axially within the bore to and from engagement with one of the helical cams and so that it is angularly adjustable about the axis of the bore to permit proper seating within the helical cam, a second generally cylindrical cam follower means similarly received within a second bore provided within the stationary support and cooperating with the other cam, each of said cam follower means including a rotatably mounted wheel that contacts the cam when the follower is moved to its cam engaging position, means limiting the angular adjustment of the followers and means effective to disengage the engaged follower and engage the disengaged follower when the sleeve reaches a predetermined location in each direction of movement.

6. An inking roll for a printing press comprising a hollow cylindrical body, a fixed shaft means extending coaxially through said body and upon which said body is journaled both for axial rotation and axial reciprocation through a predetermined amplitude, mechanism disposed within said body for effecting reciprocation thereof as it rotates including cam means secured to and movable with said body, said cam means comprising a pair of spaced sleeves coaxial with said body and provided with internal, square, helical threads of opposite pitch, separate annular members at each end of each sleeve fitted into the ends of the sleeves to prevent relative movement between these members and the sleeve and providing an eccentric cam that forms a smooth continuation with the root of the thread and extends in an inward direction, a pair of followers mounted in said shaft means with each follower associated with a different sleeve, each follower including a generally cylindrical housing which carries a member adapted to engage the threads of the associated sleeve with the housing being snugly but slideably received within a lateral bore in said shaft means so as to be movable axially of said bore to and from a position where said member engages the threads of the sleeve and so as to be rotatable about the axis of said bore to permit proper seating of said member with relation to said threads, a lever interposed between said followers and pivoted to said shaft means as a location generally centrally intermediate said followers with the ends of said lever being loosely engaged with the cam followers in a manner which limits the rotational movement of the followers about the axis of their respective bores, said lever being effective to move one follower from its disengaged to its engaged position in response to the other follower moving from its engaged to its disengaged position.

7. An inking roll for a printing press comprising a hollow cylindrical body, a pair of spaced, fixed, axially aligned spindles upon which said body is journaled both for axial rotation and axial reciprocation through a predetermined amplitude, mechanism disposed within said body for effecting reciprocation thereof as it rotates including cam means secured to and movable with said body, said cam means comprising a pair of spaced sleeves coaxial with said body and provided with internal, square, helical threads of opposite pitch, separate annular members at each end of each sleeve fitted into the ends of the

sleeves to prevent relative movement between these members and the sleeve and providing an eccentric cam that forms a smooth continuation with the root of the thread and extends in an inward direction, a stationary support member disposed intermediate the spaced spindles and secured thereto, said support member being positioned within said sleeves, a pair of followers carried by said support member with each such follower including a generally cylindrical housing having a recess therein and within which is mounted a roller with the housing being snugly but slideably received within a lateral bore in the support member so as to be laterally movable to and from positions where the wheel is in engagement with and disengaged from the thread of the sleeve and rotatable about the axis of the bore to permit proper seating within said thread, with each of the followers being associated with a different sleeve and cooperating with said threads to effect reciprocation of the inking roll, a lever interposed between said followers and pivoted to said support member at a location generally centrally intermediate said followers with the ends of the lever being received within slots in the housing of the follower in a manner permitting limited but preventing excessive rotation of the housing of the follower, said lever being effective to move one follower from its disengaged to its engaged position in response to the other follower moving from its engaged to its disengaged position with the eccentric cams in the annular members being operative to cam the engaged follower laterally to its disengaged position.

8. An inking roll for a printing press comprising a

25 cylindrical sleeve, a fixed shaft means extending coaxially through said sleeve and upon which said sleeve is mounted for rotation about its major axis and for axial reciprocation through a predetermined amplitude, a pair of internal helical cams of opposite pitch disposed within said sleeve for movement therewith and in coaxial relation therewith with the cams being in closely spaced relation, a pair of followers mounted in said shaft means with each follower associated with a different cam, each follower 10 including a generally cylindrical housing which carries a member adapted to engage the associated cam with the housing being snugly but slideably received within a lateral bore in said shaft means so as to be movable axially of said bore to and from a position where said member 15 engages the cam and so as to be angularly adjustable about the axis of said bore to permit proper seating of said member with relation to said cam and with the diameter of the housing being only slightly less than the corresponding dimension of the shaft means, means limiting 20 the angular adjustment of the followers and means effective to disengage the engaged follower and engage the disengaged follower when the sleeve reaches a predetermined location in each direction of movement.
